DESIGN FOR A PHOTOGRAPHIC ENLARGER

Rudolph Simmon, Long Island City, N. Y.

Application October 19, 1938, Serial No. 80,550

Term of patent 7 years

To all whom it may concern:

Be it known that I, Rudolph Simmon, a citizen of the United States, residing in Long Island City, county of Queens, and State of New York, have invented a new, original, and ornamental Design for a Photographic Enlarger, of which the following is a specification, reference being had to the accompanying drawing, forming a part thereof, in which the single figure is a perspective view of a photographic enlarger showing the new design.

Distinguishing features of the present design include the long cylindrical member at the top, the rod projecting upwardly therefrom, and the bellows extending downwardly below the cylindrical member, the channel support being above the bellows.

I claim:

The ornamental design for a photographic enlarger, substantially as shown and described.

RUDOLPH SIMMON.
